UNITED STATES PATENT OFFICE.

MARY A. HOUGHTON, OF BOSTON, MASSACHUSETTS.

RAISED PUZZLE FOR THE BLIND.

941,680.

Specification of Letters Patent. Patented Nov. 30, 1909.

Application filed June 5, 1909. Serial No. 500,369.

To all whom it may concern:

Be it known that I, MARY A. HOUGHTON, of the city of Boston, in the county of Suffolk and Commonwealth of Massachusetts, have invented certain new and useful Improvements in Raised Puzzles for the Blind, of which the following is a specification.

As its name implies, the object of this invention is the construction of a puzzle which can be played by the blind, which comprises an ornamented board sawed in irregular sections. While such board may be ornamented or figured in any way capable of recognition by touch alone, I prefer to have the ornamental or illustrative configurations elevated above the general surface of the board, and to have the irregular lines of severance pass indiscriminately through both board and figures, as illustrated in the drawing forming part of this specification, and which is a perspective view of a puzzle made in accordance with my invention. To better adapt the same for the blind, I provide a shallow box or tray 1 for receiving the puzzle, which tray is formed with slightly raised sides 2 within which the puzzle is designed to be fitted, and by means of which the latter is retained in position. I prefer to have the top edges of these raised sides substantially flush with the upper surface of the board 3 which composes the foundation or main body of the puzzle. This board 3 is fitted to rest upon the bottom of said tray between said edges, but not to be permanently attached to either of the last-named parts.

In the production of the puzzle, I prefer to first saw out one or more comparatively simple figures from thin board, as the camel shown in said figure, and then permanently secure the same upon said board 3, as by strong glue. Then by any suitable means, as a bracket-saw, the said board and figure are cut into irregular sections in the usual manner; the lines 4 representing the saw-scarfs, and 10 the figure. These sections being thrown into a heap, the puzzle consists in properly positioning them between the rims or raised sides 2 and upon the floor or bottom of the tray, the only means for determining the locations thereof being the "feel" of the elevated parts of the figure, aided by the touch of the edges of the board-sections also.

To materially aid the beginning of the 55 puzzle-solution, I prefer to provide a small peg or point 5 at one corner of the tray, and a similar peg or pin 6 in the board-section 3^a fitting such corner. I occasionally, in the cases of more complicated puzzles, provide each section, or any number thereof, with one or more pegs 7 located to fit holes 8 in the bottom of the tray. These pegs serve to keep the puzzle-sections from being dislodged during the task of finding and fitting 65 the remainder.

While I have described the puzzle as made by gluing a shaped figure upon a board, it is evident that the same effect can be produced by making the whole thing from papier-mâché, or other hardening material pressed in a mold; the essential thing being the production of a board having figures either raised above or sunk below the surface thereof in such a manner as to be easily recognized by touch.

By having the figures colored in contrast to the ground below, or each suitably provided with colored or printed surfaces, the puzzle is rendered equally attractive to persons who have normal sight. The puzzle is otherwise acceptable for those who are of good eyesight, as forming an amusement for blind-fold parties, playing in the twilight, etc.

What I claim as my invention and for which I desire Letters Patent is as follows, to wit;

1. A puzzle for the blind comprising a flatly extended body having its upper surface formed with configurations adapted to be determined by touch, said body being cut into indiscriminate sections bearing no relation to said configurations.

2. A puzzle comprising a board formed 95 with a characteristic outline, and a second board larger in outline and affixed to and supporting the first-named board; both boards being cut into indiscriminate sections and substantially all the sections of the 100 lower board extending beyond those of the upper.

3. A puzzle comprising a shallow tray having raised edges, a board loosely fitting between such edges upon the bottom or floor 105 of the tray, a second board having a characteristic outline affixed to the upper surface of the first-named board, both boards being

sawed into irregular sections, and substantially all the sections of the lower board extending beyond those of the upper, a projecting peg fixed to one corner of the first named board, and another peg affixed to a corresponding corner of said tray's edges.

In testimony that I claim the foregoing

invention, I have hereunto set my hand this 3rd day of June, 1909.

MARY A. HOUGHTON.
